UNITED STATES PATENT OFFICE

CHARLES AMI JACOT, OF LA CHAUX-DE-FONDS, SWITZERLAND

AUTOMATIC GAS-TAP CONTROL

Application filed February 23, 1928, Serial No. 256,281, and in Germany December 20, 1927.

My invention relates to a device for automatically closing a gas tap under the influence of a boiling liquid so as to prevent the gas and the liquid from being wasted and 5 the liquid, for instance milk or the like, from boiling over and contaminating the gas burners.

With this object in view the invention consists in the provision of a frame adapted to 10 be supported partly on the cooking vessel and partly on the gas tap and furnished with a spring controlled tap-closing element as well as with a thermostatic retaining element whereby the closing element is normally prevented from operating, the thermostatic element being suspended within the vessel and 15 adapted to open under the influence of the heat so as to release the closing element when the liquid boils.

Fig. 1 of the accompanying drawings 20 represents a side view of the device in operative position, the cooking vessel being shown in section; Fig. 2, a side view of the device alone and in inoperative position; Fig. 3, a 25 top view of the device in the operative position; Fig. 4, a front view of the device in the operative position, and Fig. 5, a rear view of the same.

The device consists of a frame composed 30 of a U-shaped wire structure one end of which is attached to a casing *o*, the other end being hooked as shown in Figs. 1 and 2 for the convenient suspension of the device. The casing *o* contains a spring *r* which controls a boss 35 having a square aperture, and in this aperture a square, vertical rod *n* is held so that it must rotate with the boss while being free to slide up and down in the same with a certain amount of friction. The lower end of the rod 40 is fitted with a shoe *p* adapted to be placed over the operating handle of the gas tap *s*, as shown by dotted lines in Fig. 1, so as to couple the rod and the boss to the tap. The boss carries a crank arm *m* situated outside 45 and above the casing *o*. The crank pin *l* of

this arm co-operates with a crank *f* formed at one end of an inclined rod *c* which is pivotally supported at *b* in a bracket connected to the casing *o*. The other end of the rod is pivotally supported at the upper end of a substantially vertical rod *e* adapted to slide with a rather tight fit in a bracket secured to the frame *a*. The rod *c* carries a double-armed lever one end *d* of which is coiled so as to form a convenient operating handle, 55 while the other end *d'* is pivoted to a rod *k* which is loosely guided in a bracket *v* secured to the lower part of the rod *e* which is formed at its lower end with a hook or crutch *i*. The lower end of the rod *e* carries a ring *g* which 60 is cut open at *h* and notched so as to form an oval gap *h'* wherein the hook *i* can be gripped. The ring *g* is laminated and formed of two metals with different coefficient of expansion, the metal with the greater expansion 65 being situated inside and the other outside the ring. For instance the inside of the ring may be composed of brass and the outside of steel. Owing to this composition, the ring will tend to straighten out so as to widen 70 the gap *h'* under the influence of heat. The rod *k* carries a collar *u* which is adapted, by abutment against the bracket *v*, to limit the downward movement of the rod. The bearings 75 of the rod *c* are large enough to allow this rod to be deflected and the rods *e* and *k* to be adjusted in their supports, as indicated by dotted lines in Fig. 1. The rotary movement of the crank *f* is limited by a wire bracket *t* secured to the casing *o*. 80

The action is as follows:

The part A of the device is supported by means of the frame *a* over the cooking vessel *g*, and the part B is supported by means of the shoe *p* on the gas tap *s*, the rod *n* being 85 adjusted in the casing *o* so as to maintain the frame in a substantially horizontal position. Previous to the application of the device, the lever *d*, *d'* is turned so as to put the hook *i* into engagement with the ring *g*. The rod 90

c turns with the lever and the movement of the rod and of the crank *f* causes the arm *m* to be turned so as to tension the spring *r*. The shoe *p*, which participates in the movement will then be in a position to engage the open gas tap *s*. The ring *g* is normally capable of retaining the rod *k* in opposition to the action of the spring *r* which tends to restore the elements to their normal positions. When the 10 device has been placed in position on the vessel *g* and on the gas tap, the rods *e* and *k* are adjusted in their supports so as to hold the ring *g* in a suitable position either above or below the surface of the liquid. In the case 15 of milk the ring should be held immediately above the surface. In the case of coffee or the like, it should be placed below the surface. As soon as the liquid attains boiling temperature, and, in the case of milk, rises into contact with 20 the ring *g*, the latter, owing to its expansion, releases the rod *k*, and the spring *r* then restores the elements to their normal positions and at the same time turns and closes the gas tap *s* so as to extinguish the flame under the 25 cooking vessel.

I claim:

1. An automatic gas tap controlling device comprising an elongated frame, a rotatable, spring-controlled rod supported at one end of 30 the same, means for connecting said rod operatively with the gas tap, a spring co-operating with said rod, a crank mechanism for turning said rod in opposition to said spring, a thermostatic retaining element supported 35 at the opposite end of the frame, and an arresting rod adapted to be moved by said crank mechanism into engagement with the retaining element when the tap operating rod is tensioned, the retaining element being normally engaging the arresting rod to hold said 40 tap open and to release the operating rod on attaining a given temperature to permit said spring to close the tap.

2. The device claimed in claim 1 in combination 45 with a boss arranged as a motion transmitting medium between the tap operating rod and its spring, the rod being axially slid- able in said boss.

3. The device claimed in claim 1 in combination 50 with a boss arranged as a motion transmitting medium between the tap operating rod and its spring, and a crank arm mounted on said boss for co-operation with the crank mechanism, the tap operating rod being axially slid- 55 able in said boss.

4. The device claimed in claim 1 in combination 60 with a rod carrying the retaining element and one of the bearings for the crank mechanism, a bracket on the frame, the rod carrying said element being slidably mounted 65 in said bracket for varying the position of the retaining element relative to the frame.

5. The device claimed in claim 1 in combination 70 with a rod carrying the retaining element and one of the bearings of the crank

mechanism, a bracket on the frame, the rod carrying said element being slidably mounted in said bracket for varying the position of the retaining element relative to the frame, means on said element carrying rod for guiding the arresting rod, and a collar on the arresting rod adapted to limit the movement of the latter by engagement with said guiding means.

In testimony whereof I affix my signature. 75
CH. AMI JACOT.
